UNITED STATES PATENT OFFICE.

HARRY H. HANCOCK, OF SWAMPSMOTT, MASSACHUSETTS.

MEANS FOR MAKING UP AND PILING PAGES OF TYPE.

1,063,027.

Specification of Letters Patent.

Patented May 27, 1913.

Application filed October 29, 1912. Serial No. 728,436.

To all whom it may concern:

Be it known that I, HARRY H. HANCOCK, a citizen of the United States of America, residing at Swampscott, in the county of 5 Essex and State of Massachusetts, have invented certain new and useful Improvements in Means for Making Up and Piling Pages of Type, of which the following is a specification.

10 This invention relates to means for making up and piling pages of type, and one object of the invention is to provide means whereby pages of type or engravings such as those on stone, metal, etc., may be held 15 together in a pile or stack after the composition is completed and after the page is made up ready to be printed for a book, catalogue, etc.

As is well known, it is necessary in all 20 printing shops where book and catalogue work is done to keep a great deal of type standing in page forms. Take a thirty-two page catalogue for instance. It is customary to bind the page of type around with 25 a string for the purpose of holding the type together until the page is ready to be printed. There is an accumulation of a great number of pages of type in a shop depending more or less upon the amount of work done, and 30 these accumulated pages of type take up considerable floor or bench space. Pages of type are piled or stacked to a greater or less height, but this height is very much restricted because under the method heretofore practised, one page of type after the 35 other is placed upon a piece of cardboard and the whole weight of type or plates or blocks comes onto the face of the type, and a pile of more than a dozen pages or so 40 would be unsteady and therefore impracticable.

Under the present invention it is possible to pile or stack a great many pages of type in one pile. For example thirty-two pages 45 of type can, under the present invention, be placed in one pile or stack, and practically seventy-five per cent. of the space now occupied for the storage of type pages can be saved.

50 Another object of the present invention is to provide means for protecting the type faces and engravings from dust and dirt which is always collecting in most of the printing establishments.

A further object of the invention is to 55 provide two or more unit members for a pile or stack, which members are so constructed and adapted to each other that one may be placed on top of the other up to the desired height, and the said members 60 will be interlocked or secured together.

A further object of the invention is to provide a unit member or plate for a pile or stack, which member or plate is so constructed as that the page of type may 65 be readily slid onto the same with the least amount of handling and placed in a pile or stack.

A further object of the invention is to provide for a pile or stack of pages of type 70 or engravings of more or less height, and any of which pages of type or engravings may be rendered easily accessible in the pile or stack by lifting that portion of the pile or stack which is above the page of type 75 to which access is desired. In other words, any page of type is rendered easily and quickly accessible, whereas under the former method one page of type after the other has to be lifted in order to get access to a page 80 of type in the lower part of the pile.

These being among the objects of the present invention, the same consists of certain features of construction and combinations of parts to be hereinafter described 85 and then claimed with reference to the accompanying drawings showing suitable forms of the invention, and in which—

Figure 1 is a perspective view of the preferred construction of unit member or 90 plate; Fig. 2 is a plan view of the same, the rectangular figure of broken lines indicating a page of type resting on said plate or member; Fig. 3 is an underside view, reduced here, of one end of the unit member 95 or plate shown in Figs. 1 and 2; Fig. 4 is a section on the line 4—4 Fig. 1; Fig. 5 is a transverse section which may be considered as taken on the line 5—5 Fig. 2 but which shows a pile or stack of unit members or 100 plates consisting of two, the pages of type being indicated in broken lines; Fig. 6 is a perspective view showing one of the unit members or plates and illustrating how it may be used to slide a page of type or a 105 block onto it; Fig. 7 is a transverse section of another construction of unit member or plate; Fig. 8 is a plan view of a modi-

5 fication illustrating a unit member adapted for use as a printer's galley and by which the composition may be effectuated; Figs. 9 and 10 are respectively sections on the lines 9—9 and 10—10 of Fig. 8; and Figs. 11, 12, 13 and 14 are views indicating different ways in which the sides of the unit members or plates may be bent to facilitate piling or stacking.

10 Referring to Figs. 1 to 6 inclusive, the unit member consists of a plate 11 of oblong rectangular shape and which is provided at opposite edges with bent up portions which comprise longitudinal corrugations or ribs 12—12 which project above one surface of said plate 11, longitudinal side flanges 13—13 which are bent up from the outer portions of said corrugations or ribs 12 and extend away from the opposite surface of 15 said plate, while at the outer edges of said flanges outwardly extending longitudinal lips or shoulders 14—14 are provided. These lips 14—14 are transversely curved or troughed at substantially the same transverse curvature of the ribs or corrugations 20 12—12. This is necessary because the corrugations or ribs 12—12 of another plate or unit member as shown in Fig. 5 are to be seated in the gutters or troughs of the lips or shoulders 14—14. On the surface of said 25 plate 11, preferably on that surface from which the ribs or corrugations 12—12 protrude is a soft or yielding covering or facing 15 which is indicated in broken lines in Fig. 2. This facing or covering may consist of any suitable soft or yielding material such as felt, which is in the form of a sheet and which is glued or pasted or otherwise secured to the underside of the described 30 unit member. This facing or covering of soft material has an area approximately of that defined by the length of the longitudinal bent up portions 13—14 and the distance between the opposite bent up portions. 35 Said unit member or plate is also preferably provided at each end with blades or extensions 16—16, which serve the purpose of handles for lifting the plate and page of type thereon indicated by the rectangular broken view in Fig. 2, and which also serve 40 as shoveling blades for the purpose of introducing a page of type or an engraving upon it in the manner as shown in Fig. 6.

45 Fig. 5 shows the manner of making use of the subject of the present invention, and in this figure only two unit members or plates are illustrated because it is apparent that any number may be piled one on top of the other in the same manner as shown in said 50 figure. It will be seen that the lower unit member which supports a page of type or engraving also supports the unit member next above it, as the unit members for a given pile or stack are all of approximately 55 the same dimensions. The ribs or corruga-

tions 12—12 of the second unit member or plate will be fitted and seated on the lips 14—14 of the next lower unit member so that an engaging connection is provided. It will also be noted that the soft facing or covering 70 on the bottom of the second unit member will be positioned between the bent up portions of the lower unit member. When a page of type or engraving is placed in one of the unit members, the engraved surface 75 or type faces will be presented upwardly and when a second unit member is placed on that, its soft facing or covering if it has one will come in contact with and protect said type faces or engraved surface; the same holds 80 as to each unit member with its contained page of type which is placed on the stack or pile. Of course there may be different sizes of unit members for different sizes of pages of type if desired. It will be apparent by 85 reference to the figures in cross-section that the bent up portions are constructed or formed to advantage, with a view to strength in particular. The side flanges 13—13 at 90 opposite edges of each unit member or plate converge toward each other so that the cross-section of each bent up portion is approximately of Z shape. One advantage of these bent up flanges is that when a unit member supporting a page of type or an engraving 95 is placed on top of another unit member or plate, the tendency is to hold or spread apart the bent up portions of the said next lower plate or unit member. This prevents the 100 said lower unit member or plate from buckling or bending due to the weight of the page of type or engraving on it. Also by referring to Fig. 5 it will be seen that the proportions of the unit members for a given pile are such that the space between adjacent plates is somewhat higher than the type or engraving so that said plates are spaced apart a sufficient distance to absolutely avoid 105 contact of the lower surface of the upper plate with the printing surface located thereunder. It is obvious therefore that a soft 110 facing may or may not be used.

In Fig. 7 a modified form of the invention is shown, the unit member 17 being of substantially the same cross-section as the ones 115 before described, but the using position of the same is reversed, and the soft or yielding facing or covering 18 is glued or secured to that surface of the unit member from which the bent up portions project. In a 120 pile of such unit members the page of type or engraving will not be positioned in the pocket or space of the unit member which supports it but in the pocket or space of the unit member which supports the next higher 125 page of type or engraving.

In Figs. 8, 9 and 10 another modification is illustrated. In this form of the invention each unit member is particularly adapted 130 for use as a printer's galley to be used in

composition. With this end in view, the unit member 20 is preferably formed and constructed with three inclosing sides or walls 21 and 22—22. The end wall 21 is 5 preferably a plain vertical wall or side while the sides proper 22—22 are also arranged as vertical walls, but the said sides are connected with the sides of the unit member or plate 20 by means of doubled-over edge portions 23—23. These edge portions and 10 the sides 22—22 are preferably bent up from the same piece of metal as the plate 20, and the edge portions 23—23 are in the form of ribs which diverge from the side edges of 15 the plate. The upper edges of the side walls 22—22 are provided with longitudinal and outwardly projecting lips 24—24, so disposed that the lips of one unit member will be complementary to the ribs 23—23 of 20 another member to be supported on it, in the same way as the unit members are supported in the form of the invention shown in Fig. 5. As in the preferred form of the invention, the underside of each unit member 25 is provided with a soft facing or covering 25 and there is a blade or extension 20^a at its open end. Unit members constructed as illustrated in Figs. 8, 9 and 10 will support and protect pages of type or engravings in substantially the same way as in any 30 of the other forms of the invention. As stated, the construction shown in said figures adapts each unit member for use as a galley, and this is due to the fact that the unit member 35 is provided with three inclosing side walls which extend at right angles to the plate 20 to facilitate making up and composition.

No particular description of the forms of 40 bent up side portions of a unit member as illustrated in Figs. 11, 12, 13 and 14 is necessary as the said views speak for themselves. They simply show modifications in the manner of bending up the sides of each unit member, which is to constitute a unit of a 45 given pile or stack. It will be noticed that each unit member has a pocket with an open-side so that said pocket may be termed an open-side pocket, that is to say at least one 50 side of said pocket has no wall.

It is obvious that the present invention is susceptible of other and still further modifications, but the forms of the invention disclosed are sufficient to illustrate the character and scope of the invention.

What I claim as new is:—

1. A printer's device of the class described, comprising a plate provided on one side with side flanges for forming a pocket to 60 receive a page of type, and on the other side with an attached soft or yielding facing, and shoulders or lips extending from the outer edge portions of said flanges.

2. A printer's device of the class described, 65 comprising a plate provided on one side with

side flanges for forming a pocket to receive a page of type, and on the other side with an attached soft facing, and suitable means at the upper and lower edges of said flanges adapted to connect with or interlock with 70 other such printer's devices.

3. A printer's device of the class described, comprising a plate provided with a pocket to receive a page of type, and also having means for protecting the type faces or engravings, said plate being provided with 75 projecting means at opposite edge portions of both surfaces, extending away from each other, and engaging connections on one of said projecting means.

4. The combination of two or more interlocking or nested devices for piling and separating pages of type, each comprising a plate provided with an open-side pocket to receive a page of type, the upper plate or 85 plates having means for protecting the type faces or engravings of the pages of type beneath.

5. The combination of two or more freely detachable devices for piling and separating 90 pages of type, each comprising a plate having side flanges to form an open-side pocket for receiving a page of type, and the flanges being constructed to interlock or be connected with other plates.

6. The combination of two or more devices for piling and separating pages of type, each comprising a plate having side flanges to form a pocket for receiving a page of type, and the flanges being constructed to interlock or be connected with other plates, and each plate having a soft facing attached to the bottom for protecting the type faces or 100 engravings by contact.

7. A printer's device of the class described, 105 comprising a flat plate, longitudinal corrugations or ribs on one side of said plate near its opposite edges, flanges extending directly oppositely away from said ribs on the other side of said plate, and seats formed at the free edges of said flanges and spaced the same distance apart as said corrugations or ribs.

8. A printer's device of the class described, 115 comprising a flat plate, longitudinal corrugations or ribs on one side of said plate near its opposite edges, flanges extending away from said ribs on the other side of said plate, seats formed at the free edges of said flanges, and a soft facing on one surface of said plate 120 for protecting the type faces and engravings by contact.

9. The combination of a plurality of plates 125 adapted to receive a printing surface between them, provided at each of two opposite edge portions with engaging means presented both upwardly and downwardly from the surfaces of said plates, whereby one plate may be seated and engaged by said means with the other plate; said plates being 130

spaced apart a sufficient distance to avoid contact of the lower surface of the upper plate with the face of the printing surface located thereunder.

5 10. A printer's device of the character described comprising a plate, projecting means at opposite edge portions of both surfaces of

said plate, extending away from each other, and engaging connection on one of said projecting means.

HARRY H. HANCOCK.
